(57) **CLAIM**

The ornamental design for a film dispenser for use with
coreless film roll, as shown and described.

DESCRIPTION

FIG. 1 is a perspective view of a film dispenser for use with
coreless film roll showing our new design in a disengaged
configuration;

FIG. 2 is a front view thereof;
FIG. 3 is a top view thereof;
FIG. 4 is a rear view thereof;
FIG. 5 is a bottom view thereof;
FIG. 6 is a perspective view of the film dispenser of FIG. 1
in an alternative engaged configuration;
FIG. 7 is a perspective view of a female film dispenser half
shown separately for clarity;
FIG. 8 is a front view thereof;
FIG. 9 is a top view thereof;
FIG. 10 is a rear view thereof;
FIG. 11 is a bottom view thereof;
FIG. 12 is a right side view thereof;
FIG. 13 is a perspective view of an embodiment of a male
film dispenser half shown separately for clarity;
FIG. 14 is a front view thereof;
FIG. 15 is a top view thereof;
FIG. 16 is a rear view thereof;
FIG. 17 is a bottom view thereof; and,
FIG. 18 is a left side view thereof.

The right and left side views form no part of the claimed
design of the film dispenser of FIGS. 1-6.

The left side view forms no part of the claimed design of the
female film dispenser half of FIGS. 7-12.

The right side view forms no part of the claimed design of
the male film dispenser half of FIGS. 13-18.

The dot dash lines shown in the figures that are immediately
adjacent to the shaded areas and define unshaded regions
represent the bounds of the claim, while all other broken
lines illustrate the portions of the design that form no part of
the claimed design. None of the broken lines form any part
of the claimed design.
